UNITED STATES PATENT OFFICE.

BARNEY H. SANDERS, OF ST. LOUIS, MISSOURI, ASSIGNOR TO THE ETTE & HENGER MANUFACTURING COMPANY, OF SAME PLACE.

DESIGN FOR A BRACKET.

SPECIFICATION forming part of Design No. 21,199, dated December 1, 1891.

Application filed October 29, 1891. Serial No. 410,281. Term of patent 14 years.

To all whom it may concern:

Be it known that I, BARNEY H. SANDERS, a citizen of the United States, residing at St. Louis, in the State of Missouri, have invented and produced a new and original Design for Brackets; and I do hereby declare the following to be a full, clear, and exact description of the invention, such as will enable others skilled in the art to which it appertains to make and use the same.

My design relates to a bracket, the object of the invention being to ornament and embellish the appearance of such an article by making it in a novel and peculiar shape; and it consists in the new design for a bracket, substantially as herein shown, described, and claimed.

The illustration presented in the accompanying drawing is a side elevation of a bracket, showing my design.

The leading features of my design are comprised in a figure having right-angled edges, the quadrant at the vertex of said edges having an ornamental and dentated arc line, ornamental panels parallel to the edges, and a conventional curved figure in skeleton form between the panels.

A A represent the horizontal and the vertical outer edges of my new bracket design, said edges being at right angles to each other. The space between them is partially filled with a skeleton or open work arrangement of the various parts of the design, as I shall now describe.

Within the angle between the two edges A A there is a vacant quadrant bounded by the curved connecting part B, in addition to the two parts of the lines A, which form its straight sides, said curved line B being a suitable distance from the vertex of the angle. Part B has thereon an ornamental curved panel b marked with points or dots or other suitable ornamental devices, and the part B is furthermore shaped with a series of outwardly-extending radially-directed V-shaped cusps or points D, in the center of each of which is a circular ornamenting point or dot d. The curved part B connects at each end with the adjacent side A by a flat block-like part a', whose face is depressed below the level of the series of points D, and also it will be ob-

served that the short space occupied by parts a' intervenes between the ends of said series of points D and the sides A.

Along the inner side of each of the edges A A is a panel parallel to side A. C designates the horizontal panel, and C' the vertical one. The inner ends of these panels meet the curved part B, and their outer ends are contiguous to the ends of edges A. Said panels have a convenient width, so that their faces may be embellished with devices consisting of an indented or dotted background traversed from end to end by the conventional figure of a sinuous vine-like rib c, with offshoots c' alternately on opposite sides of rib c, which shoots carry fruit-like forms c² and pointed ends. The panels C C' are connected with the adjacent edges A by intervening rectangular block-shaped pieces a, similar to pieces a', which are separated from each other by vacant spaces, as shown. It will thus be seen that the panels C C' lie in positions at right angles to each other. Within the space between them is a curved conventional figure comprising an outer curved arm E, which is situated in a substantially inclined position and extends substantially in the direction of a line connecting the outer ends of panels C C' or of edges A, said panels being touched by the ends of arm E. Springing from arm E into the space between it and panels C C' is a compoundly-curved figure G, the upper curve of which touches the inner edge of horizontal panel C, while the lower curve touches the inner edge of the vertical panel C'. This lower curve terminates in an independent cornute or horn-shaped form G', having an ornate, dentated, or foliated edge set vertically, and within the winding of the upper curvature of figure G is another similar cornute form G², set horizontally and with its oppositely-projecting ears touching, respectively, the opposite edges of the inclosing figure.

At the middle point, or thereabout, of the length of arm E is a circular ring F, which touches figure G. Within the ring F is a polyfoil f', inclosing a central star f, and itself encircled by a series of dots or points, which ornament the surface between the polyfoil and the concentric ring F. At the outer end

OVER

of the panel C is a dentated ornamental terminal *c*, and at the bottom end of panel C' is a similar though differently-shaped terminal *g*.

5 What I claim is—

The design for a bracket, substantially as herein described and shown.

In testimony whereof I affix my signature in presence of two witnesses.

BARNEY H. SANDERS.

Witnesses:

GEORGE JONES,

HERMAN BIERMANN.
